PEDESTAL TYPE ELECTRIC OUTLET BOX

Charles du B. Arcularius, New Canaan, Conn., assignor to Laboratory Furniture Co., Inc., Long Island City, N. Y., a corporation of New York

Application September 22, 1949, Serial No. 5,129

Term of patent 14 years

(Cl. D26—1)

To all whom it may concern:

Be it known that I, Charles du B. Arcularius, a citizen of the United States and a resident of New Canaan, county of Fairfield, and State of Connecticut, have invented a new, original, and ornamental Design for a Pedestal Type Electric Outlet Box, of which the following is a specification, reference being had to the accompanying drawing, forming a part thereof, in which:

Figure 1 is a perspective view of a pedestal type electric outlet box embodying my new design;

Figure 2 is a view in side elevation of the outlet box shown in Figure 1;

Figure 3 is a view in front elevation of the outlet box shown in Figure 1; and

Figure 4 is a top plan view of the outlet box shown in Figure 1.

The broken lines shown in Figure 1 of the drawing have been omitted from the remaining views for convenience of illustration.

The dominant feature of my design resides in that portion shown in full lines in the drawing.

I claim:

The ornamental design for a pedestal type electric outlet box, as shown and described.

CHARLES du B. ARCULARIUS.
